ABSTRACT OF THE DISCLOSURE

An apparatus for automatically discharging urine is comprised of a portable urinal interconnected by flexible conduits and electric cable with a suction pump, an electric motor and an electromagnetic valve for alternatively and selectively withdrawing liquid waste from the urinal and for supplying wash water into the urinal. The container has a lid covering an opening through which urine is received into the urinal and a lever is connected to the lid for ease in displacing it into the open position. A pair of electric switches are mounted together on the side of the urinal for operating the suction pump and the valve for removing liquid waste from the urinal and for supplying wash water into the urinal. The liquid waste is conveyed from the urinal to a reservoir from which it is subsequently emptied.

SUMMARY OF THE INVENTION

This invention relates to an improved apparatus for automatically discharging urine whereby urine discharged into a portable urinal is conveyed to a reservoir by the action of suction pump and thereafter is emptied from the reservoir.

The object of this invention is to provide a very useful apparatus for discharging urine which can be easily operated by a person who is infirm because of age or illness by using only one hand for the operation of two switches, the one for electrically initiating the suction pump and the other for operating a valve for wash water.

Further objects and advantages of this invention will be apparent from the following detailed description of a presently preferred embodiment thereof, which is illustrated in the accompanying drawings.

IN THE DRAWINGS

FIG. 1 is a side view of a urinal according to the present invention, and

FIG. 2 is a side view of an apparatus embodying the present invention for discharging urine from the urinal shown in FIG. 1.

Referring to the drawing, the apparatus for discharging urine comprises a portable urinal 1 having an opening 2 arranged to be directed towards privy parts. The opening 2 is closed with a lid 4 which may be opened by a lever 3 attached thereto. The urinal is also provided at the top with a wash water inlet opening 8 connected to a wash water pipe 7 and at the bottom with a urine outlet opening 6 connected to a urine discharge pipe 5.

As shown in FIG. 2, in addition to the urinal 1, the apparatus for discharging urine according to this invention also comprises a main body having a urine reservoir 9, a wash water tank 10, a suction pump 11, an electric motor 12, a device 13 for absorbing foul odors and an electro-magnetic valve 14 for changing from the suction of urine into that of water in the tank 10. The urine discharge pipe 5 is connected to a urine inlet opening 15

2

leading into the reservoir 9, the opening having a one way valve. The wash water pipe 7 is in communication with the wash water tank 10 by means of the electro-magnetic valve 14.

5 The cable 16 of the electric circuits for the motor 12 and the electro-magnetic valve 14 is united in a flexible bundle with the urine discharge pipe 5 and the wash water pipe 7 and is connected to a motor switch 17 and a switch 18 for the electro-magnetic valve, both of which are mounted together on one side of the urinal 1. Switch 17 starts and stops the motor 12 and switch 18 opens and closes the electro-magnetic valve 14.

10 As is obvious from the above description the motor 12 and the electro-magnetic valve 14 are operable by the switches 17, 18 mounted on the urinal 1, so that any person who is infirm due to age or illness can easily operate the apparatus for the automatic disposal of urine.

15 While specific embodiments of the invention have been shown and described in detail to illustrate the application 20 of the inventive principles, it will be understood that the invention may be embodied otherwise without departing from such principles.

25 What is claimed is:

1. A portable apparatus for automatically disposing 30 of urine comprises a container serving as a urinal and having an opening for receiving urine therein, an outlet from said container for discharging liquid waste therefrom, an inlet spaced from said outlet for delivering wash water into said container, a liquid waste reservoir 35 remote from said container, a first conduit interconnecting the outlet from said container and said reservoir, a wash water tank disposed remote from said container, a second conduit interconnecting the inlet to said container and said wash water tank, and means for selectively alternatively withdrawing waste liquid from said container into said urine reservoir and for supplying wash water from said tank into said container.

2. A portable apparatus as set forth in claim 1, wherein 40 a lid is arranged for closing the opening in said container, means for pivotally attaching said lid to said container, and a lever is secured to said means for ease in displacing the lid from said opening.

3. A portable apparatus as set forth in claim 1, wherein 45 in said container has a rounded shape with the opening for receiving urine in the upper portion thereof, said outlet from said container located in the lower portion thereof, and said inlet for wash water located in the top portion of said container.

4. A portable apparatus as set forth in claim 1, wherein 50 in said means for withdrawing waste liquid from and for supplying wash water to said container comprises a suction pump, an electric motor for operating said suction pump, and an electromagnetic valve having a first position for withdrawing liquid waste from said container and a second position for supplying wash water into said container, said pump, electric motor and valve mounted together as a unit.

5. A portable apparatus as set forth in claim 4, wherein 55 in a first electric switch and a second electric switch are mounted together on said container, an electric cable interconnecting said switches and said electric motor and valve, said first switch arranged to start and stop said electric motor and said second switch arranged to selectively dispose said valve in one of its first and second positions.

6. A portable apparatus as set forth in claim 5, wherein 60 in said container is flexibly and portably secured to said unit comprised of said suction pump electric motor and valve by means of said electric cable and said first and second conduits.

7. A portable apparatus as set forth in claim 6, wherein means are disposed in communication with said liquid waste reservoir for removing foul odors therefrom.
